ARTIFICIAL HAND

Annar F. Syverud and Bertil G. Peterson,
Minneapolis, Minn.

Application December 8, 1947, Serial No. 790,266

13 Claims. (Cl. 3—12)

1

The present invention has relation to an artificial hand.

This application is a continuation in part of our pending application Serial No. 640,814, for Artificial Hand, filed January 12, 1946, and presents features and characteristics of construction which are improvements over the disclosure of said application.

An object of the invention is to provide an artificial hand which will include novel and improved mechanism adapted to be actuated to cause a thumb and fingers of the artificial hand to be moved from open to partially closed or completely closed position and from closed or partially closed to open position and a novel and improved construction and arrangement adapted to prevent the thumb and fingers of the artificial hand from being moved toward open position from closed or partially closed position when this is intended.

A further object is to provide a new and improved artificial hand which will include a thumb and finger normally in open condition, actuating means for selectively causing said thumb and finger to be moved from open to partially or completely closed condition and from closed or partially closed to open condition, and a construction and arrangement under the control of said actuating means for selectively locking said thumb and fingers in closed or partially closed condition and releasing the thumb and fingers to be movable to open condition by said actuating means.

And a further object is to provide a new and improved artificial hand which will include resilient means adapted to normally maintain a thumb and fingers of said artificial hand in open condition, mechanism adapted to be actuated against the potential of said resilient means to cause said thumb and fingers to be moved from open to partially or completely closed condition, and devices adapted to be actuated in response to a manipulation of the mechanism causing said thumb and fingers to be moved from open to partially or completely closed condition to cause the thumb and fingers to be positively locked in any non-open condition to which moved by said mechanism and to be actuated in response to a manipulation of the mechanism next succeeding a manipulation of said mechanism which caused said thumb and fingers to be moved from open to partially or completely closed condition to cause the thumb and fingers to be released thus to permit said resilient means to move said thumb and fingers to open condition.

2

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

15 Fig. 1 is a perspective view of an artificial hand made according to the invention;

Fig. 2 is a detail sectional view, taken substantially on line 2—2 in Fig. 3, showing the thumb and fingers of the artificial hand as when in a closed condition;

Fig. 3 is a fragmentary top plan view of the artificial hand, a cover for the body member of said artificial hand being removed;

Fig. 4 is a detail sectional view, taken on line 25 4—4 in Fig. 5, disclosing operative elements of the artificial hand situated relative to each other substantially as in Fig. 2;

Fig. 5 is a top plan view of the operative elements shown in Fig. 4;

30 Fig. 6 is a detail sectional view, taken as on line 6—6 in Fig. 4;

Figs. 7, 8 and 9 are views, partially in section and partially in elevation, disclosing the operative elements shown in Figs. 4 and 5 in several of the 35 different positions said operative elements assume during practical operation of the artificial hand; and

Fig. 10 is a detail sectional view, taken on line 10—10 in Fig. 9.

40 A body member of the artificial hand, made in simulation of the metacarpus of a human hand, is denoted 15, a thumb upon said body portion is represented 16, and fingers upon the body member are indicated 17. Said body member 15 houses a chamber 18, and a removable cover for said chamber is designated 19. A shank 20 is for attachment of the artificial hand to a member retained upon the arm or shoulder of a human being.

45 The thumb 16 is pivotally supported, as at 21, upon the body member 15 for swinging movement in a plane passed perpendicularly through the thickness of said body member, and an interior end portion of said thumb 16 lies within 50 the chamber 18. A link 22, within the chamber

55

18 and for a purpose to be made plain, has its forward end pivotally secured, as at 23, to an upwardly and rearwardly extending piece 24 rigid with the thumb 16. Resilient cushioning material on said thumb 16 is represented 25.

The fingers 17 are rigidly connected to each other and are pivotally supported, as at 26, upon the body member for swinging movement in a plane passed perpendicularly through the thickness of said body member, toward and away from said thumb 16. An interior end portion of a unit constituting said fingers 17 lies within the chamber 18. A link 27, within said chamber and for a purpose to be set forth, has its forward end pivotally secured, as at 28, to a rearward portion of the unit constituting the fingers 17 at a location spaced downwardly from the pivotal support 26 for said unit. As disclosed, the forward end portion of the link 27 is freely situated on a concavity in a rearward, lower portion of said unit constituting said fingers 17. Resilient cushioning material on said fingers 17 is indicated 29.

Resilient means for normally maintaining the thumb 16 and the fingers 17 in open position includes a pushrod 30 within the chamber 18 having its forward end pivotally supported, as at 31, upon a portion of the unit constituting the fingers 17 at a location spaced downwardly from said pivotal support 26. The pushrod 30 extends rearwardly into a longitudinally extending well 32 in the body member 15. A compression coil spring 33, upon the pushrod 30, has one of its ends engaged against a transverse wall of the body member 15 and its other end engaged against a collar 34 fixed on a forward portion of said pushrod 30. The construction and arrangement will be such that the compression coil spring 33 will normally urge the fingers 17 to their open hand position.

Mechanism adapted to be actuated against the potential of the compression coil spring 33, to cause the thumb 16 and the fingers 17 to be moved from open to partially or completely closed condition, includes an actuating lever 35 and an actuated lever 36 both situated in the chamber 18 and having their lower end portions pivotally supported upon a pivot pin 37 situated in a lower portion of said chamber 18 and mounted in the body member to extend transversely thereof in parallel relation to the pivotal supports 21 and 26 for the thumb 16 and the fingers 17.

The actuating lever 35 consists of an elongated, inverted U-shape upper member 38 and a block shape lower member 39. The U-shape upper member 38 includes an upper base 40 and spaced apart, parallel downwardly extending arms 41, 41. The upper base 40 extends widthwise of the body member 15, and the spaced apart, parallel arms 41, 41 extend in the direction of the thickness of said body member. The block shape lower member 39 is rigidly secured to and situated between lower portions of the spaced apart, parallel arms 41, 41 and extends downwardly and rearwardly, and an end portion of said block shape lower member 39 is supported upon said pivot pin 37.

The actuated lever 36 is of U-shape. It includes a base 42 and spaced apart, parallel, forwardly extending side portions 43, 43. The base 42 and spaced apart, parallel side portions 43, 43 of said actuated lever extend in the direction of the thickness of the body member 15 in a plane disposed perpendicularly to and longitudinally of said body member and including the actuating

lever 35. A downwardly projecting ear 44 on each side portion 43, spaced apart a distance a trifle greater than a measurement representing the width of the block shape member 39, are situated at the corresponding side of a lower portion of said member 39 and said projecting ears are supported upon the pivot pin 37.

Intermediate parts of the spaced apart, parallel, forwardly extending side portions 43, 43, in spaced relation to the pivot pin 37, support a pivot pin 45 which extends widthwise of the body member 15 in parallel relation to said pivot pin 37, and said pivot pin 45 in turn rotatably supports the forward ends of the links 22 and 27, respectively. Said links 22 and 27 are at the outer sides of the spaced apart arms 41, 41 of the upper member 38 of the actuating lever 35 and also at the outer sides of the side portions 43, 43 of the actuated lever 36 desirably in proximate relation to said side portions 43, 43.

A flat L-shape spring 46, having one of its end portions secured, as at 47, to the block shape lower member 39 of the actuating lever 35 and its other end portion engaged, as at 48, against a lower portion of the base 42 of the actuated lever 36, has potential to normally urge said actuating and actuated levers apart, as in Figs. 2, 3, 4 and 5 of the drawings.

An operating entity or cord 49 for the actuating lever 35, secured, as at 50, to the upper base 40, extends rearwardly of the body member 15 and out of said body member through a slot 51. The actuating lever 35 is adapted to be swung rearwardly, against resilient action of the flat L-shape spring 46, in response to manually accomplished rearward pulls upon the operating entity or cord 49, and said flat L-shape spring is adapted to return said actuating lever 35 to its farthermost forward position, against a transverse stop 52 upon the body member 15, when said operating entity or cord 49 is released.

The compression coil spring 33, which normally urges the fingers 17 to open position, also normally urges the actuated lever 36 to its farthermost forward position, which is about as disclosed in Fig. 8 of the drawings, through the instrumentality of the link 27 connected between said fingers 17 and said actuated lever 36. In turn, the thumb 16 is normally urged to open position through the instrumentality of the link 22 connected between the actuated lever 36 and said thumb.

Each time the actuating lever 35 is swung rearwardly, in response to rearward pulling of the operating entity or cord 49, the actuated lever 36 is caused to be swung rearwardly. More explicitly, the rearward edges of the spaced apart arms 41, 41 of the actuating lever 35 become engaged against the forward edges of the spaced apart side portions 43, 43 of the actuated lever 36 when said actuating lever 35 is swung rearwardly thus to cause said actuated lever to be swung rearwardly. When the actuated lever 36 is moved rearwardly, against resilient action of the compression coil spring 33, the thumb 16 and fingers 17 are caused to be moved toward closed condition through the medium of the links 22 and 27, and when said actuated lever 36 is released, said compression coil spring 33 of course will react to cause said thumb and fingers to be moved to their completely open condition.

Devices of the artificial hand adapted to be actuated, in response to a manipulation of the actuating and actuated levers 35 and 36 causing said thumb 16 and fingers 17 to be moved from

open to partially or completely closed condition, to cause the thumb and fingers to be positively locked in any non-open condition to which moved by said actuating and actuated levers, and to be actuated, in response to a manipulation of the actuating and actuated levers next succeeding a manipulation of said actuating and actuated levers which caused said thumb and fingers to be moved from open to partially or completely closed condition, to cause the thumb and fingers to be released, thus to permit the compression coil spring 33 to move said thumb and fingers to open condition, include an arcuate locking bar 53, a locking lever 54, and an actuator element 55 for said locking lever.

The rearward end of the arcuate locking bar 53 is pivotally supported on a cross pin 56 carried by the body member 15 and said arcuate locking bar extends upwardly and forwardly of said body member within its chamber 18 in direction longitudinally of the body member and in the vertical plane of the actuating and actuated levers 35 and 36. The forward end of said arcuate locking bar supports a transverse stop 57 situated a trifle rearwardly of upper portions of the spaced apart arms 41, 41 of the upper member 38 of the actuating lever 35 when in its farthermost forward position and a short distance downwardly of the upper base 40 of said upper member of said actuating lever 35. The construction and arrangement will be such that when the actuating lever 35 is swung rearwardly, the spaced apart arms 41, 41 will be moved rearwardly along opposite sides of the arcuate locking bar 53 adjacent opposite ends of the transverse stop 57, in clearing relation to said arcuate locking bar and transverse stop.

The locking lever 54 is constituted as a block of rigid material which extends in the direction of the thickness of the body member 15 and is arranged in a plane passed longitudinally through said body member and including the arcuate locking bar 53 and the actuating and actuated levers 35 and 36. A lower end portion of the locking lever or block of material 54 is snugly situated between upstanding ears 58, 58 upon the upper ends of the spaced apart side portions 43, 43 of the actuated lever 36 and is mounted upon a pivot pin 59 supported in said upstanding ears 58, 58 for swinging movement in a plane extending longitudinally of the body member. A rectilinear slot 60 through an upper portion of said locking lever or block of material 54, above the pivot pin 59, is for passage of the arcuate locking bar 53, and the length of said rectilinear slot is substantially equal to a measurement representing the thickness of said arcuate locking bar. The upper end of the rectilinear slot 60 is defined by a knife edge 61 at an intermediate portion of the locking lever 54 and extending widthwise of the body member 15, a flat surface 62 extending forwardly from the knife edge 61 in perpendicular relation to said locking lever and a flat surface 63 extending rearwardly and upwardly from said knife edge 61 in oblique relation to the locking lever. The lower end of said rectilinear slot 60 is defined by a knife edge 64 at an intermediate portion of said locking lever 54 and extending widthwise of said body member 15, a flat surface 65 extending rearwardly from the knife edge 64 in perpendicular relation to the locking lever and a flat surface 66 extending forwardly and downwardly from said knife edge 64 in oblique relation to said locking lever. The flat surfaces 62 and 65 are in parallel planes, as are

also the flat surfaces 63 and 66. The construction and arrangement will be such that the locking lever 54 selectively can be situated radially, or approximately radially, of the arcuate locking bar 53, thus to cause the knife edges 61 and 64 to be free for sliding movement of said locking lever along the arcuate upper and lower surfaces or edges of said arcuate locking bar, and can be situated obliquely of the arcuate locking bar to cause said knife edges 61 and 64 to be bindingly engaged against said arcuate upper and lower surfaces or edges of the arcuate locking bar, thus to preclude sliding movement of the locking lever relative to said arcuate locking bar.

The actuator element 55 for the locking lever 54 is constituted as an oscillatable rectilinear element 67, situated between the spaced apart arms 41, 41 of the upper member 38 of the actuating lever 35, having its forward end arranged upon a pivot pin 68 mounted in forward intermediate portions of said spaced apart arms 41, 41 and supporting a working device 69 at its rearward end. A curled spring 70 on the pivot pin 68, having one of its end portions engaged against the rectilinear element 67 and its other end portion engaged against the block shape lower member 39, normally resiliently retains said actuator element 55 down against interiorly projecting stops 71, 71 supported on said spaced apart arms 41, 41 at the side of said rectilinear element 67 adjacent said lower member 39, and when the rectilinear element 67 is retained against the stops 71, 71, the actuator element 55 lies in a plane passed substantially perpendicularly and transversely through the upper member 38. The working device 69 is constituted as an elongated strip of rigid material, in alined relation with said rectilinear element 67 and loosely situated between the spaced apart arms 41, 41, fixedly supported upon guide rods 72, 72 slidably situated in longitudinally extending guideways 73, 73 in the rearward end portion of the rectilinear element 67. A small compression coil spring 74 in a pocket 75 in said rearward end portion of said rectilinear element 67, between the guideways 73, 73, normally urges the working device or elongated strip 69 to its farthest position from said rectilinear element 67, and heads 76, 76 upon the inner ends of the guide rods 72, 72 limit the extent to which said working device or elongated strip 69 can be moved in direction away from the rectilinear element 67. The construction and arrangement will be such that the working device 69 will project slightly rearwardly of the rearward edges of the spaced apart arms 41, 41 when said working device is at its farthest position from said rectilinear element 67, about as disclosed in Figs. 2, 4 and 8 of the drawings. A rearward surface or edge 77 of the working device 69 extends widthwise of the body member 15, and the lower side of said rearward surface or edge 77 is bounded by a knife edge 78 arranged in parallel relation to the pivot pin 37.

A lower portion of the locking lever 54 includes a first working surface 79 at the forward side of said locking lever and at about the elevation of the pivot pin 59 adapted to be engaged by the rearward surface or edge 77 of the working device 69 to cause the portion of the locking lever, having the rectilinear slot 60, above said pivot pin 59 to be held in rearwardly tilted position, a second working surface 80 at the forward side of said locking lever and at eleva-

tion below the pivot pin 59 adapted to be engaged by the rearward surface or edge 71 of said locking lever and at elevation below the pivot pin 59 adapted to be engaged by the rearward surface or edge 71 of said working device 69 to cause said portion of the locking lever above said pivot pin 59 to be rocked forwardly, and a flat surface 81 between the first and second working surfaces 79 and 80 over which the knife edge 78 bounding the lower side of said rearward surface or edge 71 is adapted to be slidable in upward direction.

Sliding movement in forward direction of the locking lever 54 on the arcuate locking bar 53 is adapted to be limited by engagement of an upper portion of said locking lever with the transverse stop 57, and oppositely disposed slots 82, 82 in the upper and lower surfaces of said arcuate locking bar 53 at a location adjacent the transverse stop 57 are for permitting free rocking movement of the upper portion of the locking lever 54 when the knife edges 61 and 64 are situated in alined relation with said slots.

The operative elements of the actuating mechanism of the artificial hand are situated, when the thumb 16 and the fingers 17 are in completely open position, so that the actuating lever 35 is engaged against the transverse stop 52, the locking lever 54 is in oblique relation to the arcuate locking bar 53 with the upper portion of the locking lever engaged against the transverse stop 57, the rearward surface or edge 71 of the working device 69 is engaged against the first working surface 79 of said locking lever 54, and the small compression coil spring 74 is in substantially non-collapsed condition.

The operating entity or cord 49 is pulled rearwardly when it is desired to cause the thumb and fingers to be moved to partially or completely closed condition. The spaced apart arms 41, 41 of the upper member 38 of the actuating lever 35 are swung rearwardly in response to pulling said operating entity or cord 49 rearwardly. The working device 69 is urged into engagement with the first working surface 79 to cause the small compression coil spring 74 to be collapsed and the rearward edges of said spaced apart arms 41, 41 engage the forward edges of the side portions 43, 43 of the actuated lever 36 upon rearward swinging movement of the spaced apart arms 41, 41 to cause said actuated lever 36 to be swung rearwardly. The thumb 16 and fingers 17 are moved toward closed condition, through the medium of the links 22 and 27 and against the potential of the compression coil spring 33, in response to rearward swinging of the actuated lever 36. The actuator element 55 and the locking lever 54 of course are moved rearwardly with the actuating and actuated levers, and during its rearward movement said locking lever 54 is slid rearwardly along the arcuate locking bar 53. The working device 69 engages against the first working surface 79 during rearward movement of the actuating and actuated levers and causes the upper portion of the locking lever 54 to be held swung rearwardly. It will be apparent that any tendency which the upper and lower knife edges 61 and 64, at the ends of the rectilinear slot 60, might have to become bound against the upper and lower surfaces of the arcuate locking bar 53 while the actuated lever 36 is being swung rearwardly will be overcome or removed by reason of collapse to necessary extent of the small compression coil spring 74. That is, any tendency of the locking lever 54 toward becoming frictionally

held against the upper and lower surfaces of the arcuate locking bar 53 during rearward swinging movement of said locking lever will be overcome or removed by collapse of the small compression coil spring 74 permitting the upper portion of the locking lever to swing forwardly toward radial relation to said arcuate locking bar.

Upon release of the operating entity or cord 49 after it has been pulled rearwardly, the flat L-shape spring 46 will cause the actuating lever 35 to be moved to its farthermost forward position, against the transverse stop 52.

Immediately upon commencement of movement of the spaced apart arms 41, 41 of the upper member 38 of said actuating lever 35 from a rearward position toward their farthermost forward position directly after said spaced apart arms and the actuated lever 36 have caused the thumb 16 and the fingers 17 to be moved to partially or completely closed position, the compression coil spring 33 will start its reaction to have tendency to cause the links 22 and 27 to be moved forwardly and said actuated lever 36 to be swung forwardly upon the pivot pin 37. Evidently, forward swinging movement of the actuated lever 36 by reason of potential exerted by the compression coil spring 33 will create a tendency toward movement of the pivot pin 59, rotatably supporting the locking lever 54, forwardly thus to cause the lower end portion of said locking lever to be moved forwardly before the upper end portion of the locking lever upon the arcuate locking bar 53 has tendency to be moved forwardly. And, too, as long as the actuated lever 36 is engaged against the actuating lever 35, during initial movement of said spaced apart arms 41, 41 forwardly, the working device 69 will retain the locking lever 54 tilted rearwardly by reason of engagement of said working device with the first working surface 79. Forward movement of the pivot pin 59 and the lower end portion of the locking lever 54 to a limited extent obviously will situate said locking lever at an oblique angle to the arcuate locking bar 53 adapted to cause the knife edges 61 and 64 to be bound against the upper and lower surfaces of said arcuate locking bar, about as disclosed in Fig. 4 of the drawings. Thus, the thumb 16 and the fingers 17 when caused to be moved from open to partially or completely closed condition in response to a rearward manipulation of the actuating and actuated levers 35 and 36 will become locked in the partially or completely closed condition to which moved upon release of the actuating lever 35 for movement to its farthermost forward position.

Upon forward movement of the actuating lever 35 from a rearward position which caused the thumb 16 and the fingers 17 to be moved to partially or completely closed condition and there locked, the rearward edges of the spaced apart arms 41, 41 will first become removed from the forward edges of the side portions 43, 43, and thereafter the working device 69 of the actuator element 55 will be moved forwardly to position where clear of the first working surface 79. The curled spring 70, assisted by gravity, will act to move said actuator element 55 downwardly into engagement with the stops 71, 71 upon movement of said working device 69 to position where clear of said first working surface 79.

Assuming the parts of the artificial hand to be situated as in Fig. 4 of the drawings, where said parts are disclosed as when the locking lever 54 is fast upon the arcuate locking bar 53 and the actuating lever 35 is at its farthermost forward

position, and said actuating lever to be swung rearwardly in response to rearward pulling of the operating entity or cord 49, the working device 69 will first engage the second working surface 80, and thereafter the small spring 74 will become compressed and the rearward edges of the spaced apart arms 41, 41 will become engaged with the forward edges of the side portions 43, 43. Upon commencement of movement rearwardly of the actuated lever 36, after engagement of the spaced apart arms 41, 41 with the side portions 43, 43 and by reason of rearward movement of the actuating lever 35, the lower portion of the locking lever 54 will be swung rearwardly to cause or have tendency toward causing the upper portion of said locking lever to be swung or rocked forwardly toward released relation to the arcuate locking bar and thus assist the working device 69, by reason of the resilient action of the small compression coil spring 74, to situate the locking lever in substantially radial relation to said arcuate locking bar. See Fig. 7. Upon release of the operating entity or cord 49, which can be accomplished smoothly and gradually, to permit the spaced apart arms 41, 41 of the actuating lever 35 to return to their farthest forward position, the actuated lever 36, together with the locking lever 54 as a unit, will be returned to its farthest forward position, in response to action of the compression coil spring 33, while said locking lever is retained in substantially radial relation to and the knife edges 61 and 64 are held clear of the arcuate locking bar 53 through the instrumentality of the actuator element 55.

As hereinbefore stated, sliding movement in forward direction of the locking lever 54 is arrested by engagement of an upper portion of said locking lever with the transverse stop 57 situated a trifle rearwardly of the upper portions of the spaced apart arms 41, 41 when in their farthest forward position, and the slots 82, 82 in the upper and lower surfaces of the arcuate locking bar 53 adjacent said transverse stop 57 permit free rocking movement in a rearward direction of the upper portion and in a forward direction of the lower portion of the locking lever 54 when the knife edges 61 and 64 are situated in alined relation with said slots.

The construction and arrangement will be such that the farthest forward position for the actuating lever 35 is somewhat forwardly of the farthest forward position for the actuated lever 36, and also such that upon engagement of the upper portion of the locking lever 54 with the transverse stop 57 during forward movement of the actuating and actuated levers, after release of said locking lever from the arcuate locking bar 53, the actuated lever 36 yet will be capable of having forward movement, in response to the potential of the compression coil spring 33, to cause the lower portion of the locking lever to be swung forwardly and upwardly and the upper portion of said locking lever to be swung rearwardly, thus to cause the locking lever to be situated in oblique relation, as in Fig. 8 of the drawings, to said arcuate locking bar. Forward movement of the actuated lever 36 is arrested by engagement of the upper portion of the locking lever 54 with the transverse stop 57 and of the knife edges 61 and 64 with the upper and lower surfaces of the arcuate locking bar 53 in response to forward swinging movement of said actuated lever accomplished by the potential of said compression coil spring 33.

The actuated lever 36 when released from the arcuate locking bar 53 moves forwardly with and in following relation to the actuating lever 35 until said actuated lever has reached its farthest forward position. Thereafter, said actuating lever 35 moves forwardly to its farthest forward position and causes the working device 69 to be moved forwardly relative to the locking lever 54. The lower portion of said locking lever is swung forwardly and upwardly before the withdrawal movement of said working device, and forward, upward swinging movement of said lower portion of the locking lever, in cooperation with the potential of the small compression coil spring 74, causes the working device 69 to be moved upwardly to and past alined relation with the pivot pins 68 and 59 from its position of engagement with the second working surface 80 to its position of engagement with the first working surface 79. The upward movement of said working device is accomplished with a snap action, and during upward movement the knife edge 78 of the working device slides over the flat surface 81. The working device 69 will become engaged with the first working surface 79 at about the same time the actuating lever 35 has reached its farthest forward position, and the operative elements of the artificial hand will be situated ready to be again manipulable in the manner as set forth when said working device is engaged with said first working surface and said actuating lever is at its farthest forward position.

In Fig. 8 of the drawings the actuating lever 35 is disclosed in its farthest forward position and the working device 69 is shown as when being moved in snap action fashion upwardly from the second working surface 80 to the first working surface 79, and in Fig. 9 the actuating and actuated levers are disclosed as when being pulled rearwardly.

What is claimed is:

1. An artificial hand comprising resilient means urging a finger of said artificial hand toward open condition, a first lever adapted to be actuated against potential of said resilient means to cause said finger to be moved to non-open condition and to be subjected when in said non-open condition to said potential of said resilient means, a second lever adapted to be actuated to cause said first lever to be actuated and to be released from the first lever upon completion of actuation of said first lever, and devices adapted to be actuated by said resilient means upon release of the second lever from the first lever to cause the finger to be positively locked in any non-open condition to which moved by the first lever and to be actuated by the second lever to cause the finger to be released from locked condition, said devices including a locking lever rotatably supported by said first lever and having a rectilinear slot, a pivotally supported arcuate locking bar in said rectilinear slot slidably receiving said locking lever, and an actuator element upon said second lever and supporting a working device, said locking lever including a first working surface adapted to be engaged by said working device to cause the locking lever to be tilted in one direction when said first lever is actuated by said second lever against potential of said resilient means to cause said finger to be moved to non-open condition and a second working surface adapted to be engaged by said working device to cause said locking lever to be rotated in an opposite direction when said first lever

is actuated by said second lever to cause said finger to be released from locked condition.

2. An artificial hand comprising resilient means urging a finger of said artificial hand toward open condition, a first lever adapted to be actuated against potential of said resilient means to cause said finger to be moved to non-open condition and to be subjected when in said non-open condition to said potential of said resilient means, a second lever adapted to be actuated to cause said first lever to be actuated and to be released from the first lever upon completion of actuation of said first lever, and devices adapted to be actuated by said resilient means upon release of the second lever from the first lever to cause the finger to be positively locked in any non-open condition to which moved by the first lever and to be actuated by the second lever to cause the finger to be released from locked condition to be capable of returning to open condition, said devices including a locking lever rotatably supported by said first lever and having a rectilinear slot, a pivotally supported arcuate locking bar in said rectilinear slot slidably receiving said locking lever, an actuator element upon said second lever and supporting a working device, said locking lever including a first working surface adapted to be engaged by said working device to cause the locking lever to be tilted rearwardly when said first lever is actuated by said second lever against potential of said resilient means to cause said finger to be moved to non-open condition and a second working surface adapted to be engaged by said working device to cause said locking lever to be rotated forwardly when said first lever is actuated by said second lever to cause said finger to be released from locked condition and retained in forwardly rotated position while the finger is being returned to open condition by potential of said resilient means, and means for causing said working device to become removed from said second working surface and engaged with said first working surface upon return of said finger to open condition.

3. In an artificial hand including a finger, resilient means urging said finger toward open condition, a first lever adapted to be actuated against potential of said resilient means to cause said finger to be moved to non-open condition and to be subjected when in said non-open condition to said potential of said resilient means, a second lever adapted to be actuated to cause said first lever to be actuated and to be released from the first lever upon completion of actuation of said first lever, and devices adapted to be actuated by said resilient means upon release of the second lever from the first lever to cause the finger to be locked in any non-open condition to which moved by the first lever and to be actuated by the second lever to cause the finger to be released from locked condition, said devices including a locking lever rotatably supported by said first lever, a pivotally supported arcuate locking bar slidably receiving said locking lever, and an actuator element upon said second lever, said locking lever including a first working surface adapted to be engaged by said actuator element to cause the locking lever to be tilted in one direction when said first lever is actuated by said second lever against potential of said resilient means to cause said finger to be moved to non-open condition and a second working surface adapted to be engaged by said actuator element to cause said locking lever to be rotated in an opposite direction

when said first lever is actuated by said second lever to cause said finger to be released from locked condition.

4. In an artificial hand including a finger, resilient means urging said finger toward open condition, a first lever adapted to be actuated against potential of said resilient means to cause said finger to be moved to non-open condition and to be subjected when in said non-open condition to said potential of said resilient means, a second lever adapted to be actuated to cause said first lever to be actuated and to be released from the first lever upon completion of actuation of said first lever, and devices adapted to be actuated by said resilient means upon release of the second lever from the first lever after a manipulation of said second lever causing said first lever to move said finger from open to non-open condition to cause the finger to be locked in any non-open condition to which moved by the first lever and to be actuated by the second lever in response to a manipulation of said second lever next succeeding a manipulation of the second lever which caused said first lever to move said finger from open to non-open condition to cause the finger to be released from locked condition, said devices including a locking lever rotatably supported by said first lever, a pivotally supported arcuate locking bar slidably receiving said locking lever, and an actuator element upon said second lever, said locking lever including a first working surface adapted to be engaged by said actuator element to cause the locking lever to be tilted in one direction when said first lever is actuated by said second lever against potential of said resilient means to cause said finger to be moved to non-open condition and a second working surface adapted to be engaged by said actuator element to cause said locking lever to be rotated in an opposite direction when said first lever is actuated by said second lever to cause said finger to be released from locked condition.

5. In an artificial hand including a finger, resilient means urging said finger toward open condition, a first lever adapted to be actuated against potential of said resilient means to cause said finger to be moved to non-open condition and to be subjected when in said non-open condition to said potential of said resilient means, a second lever adapted to be actuated to cause said first lever to be actuated and to be released from the first lever upon completion of actuation of said first lever, and devices adapted to be actuated by said resilient means upon release of the second lever from the first lever to cause the finger to be locked in any non-open condition to which moved by the first lever and to be actuated by the second lever to cause the finger to be released from locked condition, said devices including a locking lever rotatably supported by said first lever, a pivotally supported arcuate locking bar slidably and rockingly receiving said locking lever, and an actuator element upon said second lever, said locking lever including a first working surface adapted to be engaged by said actuator element to cause the locking lever to be tilted in one direction relative to said locking bar when said first lever is actuated by said second lever against potential of said resilient means to cause said finger to be moved to non-open condition and a second working surface adapted to be engaged by said actuator element to cause said locking lever to be rotated in an opposite direction relative to the locking bar when said first

lever is actuated by said second lever to cause said finger to be released from locked condition.

6. The combination as specified in claim 4, and a pull cord for accomplishing manual actuation of said second lever adapted to be manipulated upon release of said finger from locked condition to cause the finger to be returned from non-open to open condition under the potential of said resilient means and control of the second lever, said actuator element upon said first lever being adapted to engage said second working surface upon said locking lever to retain said finger in released condition while the finger is being returned from non-open to open condition.

7. In an artificial hand including a finger, resilient means urging said finger toward open condition, a first lever adapted to be actuated against potential of said resilient means to cause said finger to be moved to non-open condition and to be subjected when in said non-open condition to said potential of said resilient means, a second lever adapted to be actuated to cause said first lever to be actuated and to be released from the first lever upon completion of actuation of said first lever, a pull cord for accomplishing manual actuation of said second lever adapted to be manipulated upon release of said finger from locked condition to cause the finger to be returned from non-open to open condition under the control of the second lever and the potential of said resilient means, and devices adapted to be actuated by said resilient means upon release of the second lever from the first lever after a manipulation of said second lever causing said first lever to move said finger from open to non-open condition to cause the finger to be locked in any non-open condition to which moved by the first lever and to be actuated by the second lever in response to a manipulation of said second lever next succeeding a manipulation of the second lever which caused said first lever to move said finger from open to non-open condition to cause the finger to be released from locked condition, said devices including a locking lever rotatably supported by said first lever, a pivotally supported arcuate locking bar slidably receiving said locking lever, and an actuator element upon said second lever, said locking lever including a first working surface adapted to be engaged by said actuator element to cause the locking lever to be tilted rearwardly when said first lever is actuated by said second lever against potential of said resilient means to cause said finger to be moved to non-open condition and a second working surface adapted to be engaged by said actuator element to cause the locking lever to be and remain tilted in one direction while said first lever is being actuated by said second lever against potential of said resilient means to cause said finger to be moved to non-open condition and a second working surface adapted to be engaged by said actuator element to cause said locking lever to be tilted in an opposite direction when said first lever is actuated by said second lever to cause said finger to be released from locked condition and to remain tilted in said opposite direction while said pull cord is being manipulated to cause the finger to be returned from non-open to open condition.

8. The combination as specified in claim 7 wherein said locking bar rockingly receives said locking lever.

9. The combination as specified in claim 7 wherein one end portion of said locking bar is

pivotedly supported and the opposite end portion of the locking bar is free for swinging movement.

10. The combination as specified in claim 7, and means for causing said actuator element to become removed from said second working surface and engaged with said first working surface upon return of said finger to open condition.

11. In an artificial hand including a finger, resilient means urging said finger toward open condition, a first lever adapted to be actuated against potential of said resilient means to cause said finger to be moved to non-open condition and to be subjected when in said non-open condition to said potential of said resilient means, a second lever adapted to be actuated to cause said first lever to be actuated and to be released from the first lever upon completion of actuation of said first lever, and devices adapted to be actuated by said resilient means upon release of the second lever from the first lever to cause the finger to be locked in any non-open condition to which moved by the first lever and to be actuated by the second lever to cause the finger to be released from locked condition to be capable of returning to open condition, said devices including a locking lever rotatably supported by said first lever, a pivotally supported arcuate locking bar slidably receiving said locking lever, and an actuator element upon said second lever, said locking lever including a first working surface adapted to be engaged by said actuator element to cause the locking lever to be tilted rearwardly when said first lever is actuated by said second lever against potential of said resilient means to cause said finger to be moved to non-open condition and a second working surface adapted to be engaged by said actuator element to cause said locking lever to be rotated forwardly when said first lever is actuated by said second lever to cause said finger to be released from locked condition and retained in forwardly rotated position while the finger is being returned to open condition by potential of said resilient means.

12. The combination as specified in claim 11, and means for causing said actuator element to become removed from said second working surface upon return of said finger to open condition.

13. The combination as specified in claim 11, and a pull cord for accomplishing manual actuation of said second lever adapted to be manipulated upon release of said finger from locked condition to cause the finger to be returned from non-open to open condition under the control of the second lever.
